OTHER PUBLICATIONS

U.S. Appl. No. 13/612,528, filed Sep. 12, 2012, entitled Cartridges, Systems and Methods for Preparation of Beverages, 38 pages.

(Continued)

Primary Examiner — Thomas Johannes(74) *Attorney, Agent, or Firm* — Fitch, Even, Tabin & Flannery LLP(57) **CLAIM**

The ornamental design for a beverage cartridge, as shown and described.

DESCRIPTION

FIG. 1 is an upper perspective view of a beverage cartridge showing my new design;

FIG. 2 is a lower perspective view thereof;

FIG. 3 is top plan view thereof;

FIG. 4 is bottom plan view thereof; and,

FIG. 5 is a front side elevation view thereof, the rear side elevation view being identical.

Broken line disclosures in the figures show unclaimed subject matter only and form no part of the claimed design.

1 Claim, 5 Drawing Sheets(56)
